UNITED STATES PATENT OFFICE.

JAMES A. McELROY, OF KANSAS CITY, MISSOURI.

SHOCKER ATTACHMENT FOR GRAIN-BINDERS.

1,345,381.

Specification of Letters Patent.

Patented July 6, 1920.

Application filed December 20, 1918. Serial No. 267,580.

To all whom it may concern:

Be it known that I, JAMES A. McELROY, a citizen of the United States, residing at Kansas City, in the county of Jackson and 5 State of Missouri, have invented certain new and useful Improvements in Shocker Attachments for Grain-Binders; and I do declare the following to be a full, clear, and exact description of the invention, such as 10 will enable others skilled in the art to which it appertains to make and use the same, reference being had to the accompanying drawings, and to the letters and figures of reference marked thereon, which form a part of 15 this specification.

This invention relates to a shocker attachment for grain binders and one of the objects thereof is to provide an inexpensive, durable and efficient attachment which may 20 be readily connected to a known form of grain binder and so correlated therewith as to efficiently form received sheaves into shocks and deposit the shocks upon the ground with the heads of the grain upstanding so that the shocks may subsequently be 25 gathered for threshing.

With these and other objects in view, my invention consists of the parts and combinations of parts to be referred to herein- 30 after and illustrated in the drawings, it being understood that changes in form, proportion and minor details of construction may be resorted to without departing from the spirit of the invention or sacrificing any 35 of its advantages.

In the drawings,

Figure I is a perspective view of the shock forming mechanism and part of the binder to which it is applied.

40 Fig. II is a view partly in section and partly in elevation of the shock forming arms.

Fig. III is a view at right angles to the section shown in Fig. II.

45 Fig. IV is an end view of the shock forming attachment.

Fig. V is a detail perspective view of the sprocket and slip clutch, driven for the initial turning movement of the shock compressor member.

Fig. VI is a detail view of a high speed clutch for the shock compressor member.

Fig. VII is a detail view of the clutch actuator.

55 Fig. VIII is a perspective view showing

the shock compressor member and the shock forming arms, and

Fig. IX is a side view of the shock compressor member.

Referring now to the drawings by numerals of reference in which corresponding reference numerals designate corresponding parts throughout the several views:

1 designates a side frame of a binder on which is the usual drive shaft 2 provided 60 with a sprocket 3 from which motion is communicated to the movable parts of the invention. 4 designates the shock former frame which is secured to the bar 1 by the bracket arms 5 and 6 connected to one side 65 of the frame 4, the other side being secured to a frame 7 upon which the adjustable caster wheel 8 is mounted. This adjustment permits the raising and lowering of the frame 4 to compensate for varying 70 heights of grain.

Inasmuch as there is considerable side draft present in binders due to the location of the cutter bars, it is obvious that by attaching the frame 4 rigidly to the side bar 80 1 of the binder the draft will be more equally distributed on each side of the same.

In the drawings I have shown a shaft 9 mounted in bearing brackets 10 and 11 on the frame 4 and this shaft carries a sprocket 85 12 around which a chain belt 13 travels, said chain being engaged by the teeth on the sprocket 3 whereby a rotation of the shaft 2 will cause a corresponding rotation of the shaft 9. On the shaft 9 is also a beveled 90 pinion 14 meshing with a beveled gear 15 on a transverse shaft 16 to which a suitable clutch 17 is attached. One of the clutch members is adapted to be moved into and out of clutching engagement with the 95 sprocket 18 on said shaft 16, the particular construction of the clutch forming no part of my invention. The clutch is, however, capable of being moved into and out of clutching engagement by means of the 100 clutch actuating arm 19 pivoted on the crank shaft 20 and connected to the frame 4 by a spring 21. The rear end 22 of the clutch actuator 19 may be connected to a cord 23 whereby the operator from the 105 binder may move the actuator at will. If the clutch 17 is actuated so that the sprocket 18 will be driven, motion will be imparted to the chain 24 which passes around a sprocket 25 adapted to drive the shaft 26 110

anti-clockwise through the medium of a slip clutch, best illustrated in Fig. V as consisting of a spring actuated pawl 27 having clutching engagement with the teeth 28 of the pawl 29 on sprocket 25 in such a manner that the sprocket 25 may over-run the pawl when motion is imparted to the shaft 26 at a greater rotative speed than that of the sleeve 29' to which the pawl 27 is secured.

- 10 By reference to Figs. I to VII it will be observed that the shaft 26 to which the shock compressor, settling member and shock up-end is attached, is loosely journaled in the sleeve 30 and that on the sleeve 15 30 is a beveled gear 31 adapted to engage a corresponding gear 32 capable of being connected to the shaft 9 through the medium of a clutch 33. The clutch 33 is provided with an actuator 34 normally held inoperative by a spring 35. The clutch actuator, however, is adapted to be operated by means of a projection or finger 36 on the intermediate or main body portion 37 of the shock former compressing and up-ending member, 20 as will be presently explained. The compressor, shock former and up-ending member 37 has attached to it two hinged leaves 38 and 39 foldable in opposite directions as best indicated in Figs. I and VIII, the leaf 30 38 being resiliently connected to the member 37 by the rod 39', one end of which is fastened at 40 and the other end of which passes through a bracket 41 and carries a spring 42. The other member 39 has a 25 spring actuated link or rod 43 for yieldingly connecting it to the member 37 and this member is also provided with bowed or outwardly curved shock positioning arms 44 and 45, (see Figs. I, VIII and IX).
- 40 In actual practice the actual up-ending may be performed by the leaf or member 39; the member 37 serving to settle and compress the shock.

On one edge of the member 37 is a lug or 45 projection 46 adapted to contact with a lug or projection 47 on the sleeve 30, the purpose of which will be apparent hereinafter. The shaft 26 is provided with a crank arm 48 which carries a pitman 49 through which 50 one end of the crank 50 also passes, said crank being on a shaft 51 and passing through a pitman 52 engaged by the crank 53 on shaft 20. Shaft 20 also carries a crank 54 at its opposite end to which a pitman 55 is attached, said pitman engaging a crank 56 in the bearing 57 on the side of the frame 4, there being a rigid toothed gear 58 on said bearing 57 corresponding to a similar gear 59 rigid on the bearing 60 through 55 which the shaft 51 passes. The shaft construction of the crank shafts 51 and 56 are best shown in Figs. II and III in which it will be observed that the crank shafts pass through the rigid gears 58 or 59, as the case 60 may be, and rigidly engage the rods 61,

which constitute the supports and form part of the shock former, there being cradle arms or supports 62 on each of the arms 61 and these supports or arms are inwardly curved so that, in their normal position, they will 70 form swings or cradles to receive the sheaves as they pass from the conveyer 63, having previously been deposited there from the deck 64 of the binder.

Depending from the side bars of the 75 frame 4 are brackets 65 and 66 in which is journaled a curved rocker shaft 67 carrying inwardly projecting teeth or fingers 68 directed toward the shock former and this shaft 67 carries a crank 69 connected to the 80 pitman 55 so that when the shock forming arms are actuated the shaft 67 and fingers will also be operated.

Since none of the shock former mechanism can operate without operation of the 85 crank 48 or its driving shaft 26, I have provided means for locking said crank 48 against accidental operation and this means consists of a pivoted latch 70, one end of which may normally rest in the path of the 90 crank 48 and the other end of which may be attached to a rod or wire 71 fast to the projection 72 on the clutch actuator 19.

When the parts are assembled and it is desired to form the sheaves into shocks, the 95 binder will be operated in the usual way with the difference that instead of the sheaves being deposited from the deck to a fork, they will pass onto the conveyer 63 to be deposited in the shock forming slings. 100 When a sufficient number of sheaves has been received the operator will pull upon the cord 23 to clutch the sprocket 18 to the shaft 16, at the same time the latch 70 will be moved out of the path of the swinging 105 crank 48. Since the sprocket 18 will be driven by the shaft 16, motion will be communicated to the sprocket 25 on the shaft 26, this being effective in initially rotating the shock compressing member which will be 110 swung until it is passed through an arc of about 90°; then the arm 36 will come into contact with the actuator 34 to throw the gear 32 into clutching engagement with the shaft 9.

Since the gear 15, sprocket 18 and sprocket 25 constitute a reduction gearing, the shaft 26 will be initially driven at a speed considerably less than that of the shaft 9; therefore, the shock compressing 120 member will be initially swung in an arc at a relatively slow speed. When it has described an arc of about 90°, however, and thrown the clutch 33 into engagement with the gear 32 so that the shaft 26 may be 125 driven through the gear 31, the remainder of the swinging movement of 270° will be completed at a relatively high speed; therefore, it follows that the compression movement for the shock will be started at a relatively slow 130

speed and completed at a relatively high speed. As the shock compressor is moving through its arc, however, the crank 48 will be moving through its arc and the shafts 51, 5 20, 56 and 69 will also be swinging so that the rods 61 will be moving in a vertical arc because they are fast to the shafts 51 and 56 and since their gears 58 and 59 fast on the shaft 61 will roll on the fixed gears 58 10 and 59, the fingers or sling arm 62 will not only move in a vertical arc but will also slide apart. The shaft 67 is also swinging with the teeth directed downwardly so that the shock can be released from the embracing 15 arms 44 and 45 with the shock up-standing. The crank 48 is on the end of the shaft 26, and carries the pitman 49 having an elongated slot in one end which engages a crank 50 on the shaft 51. When crank 48 is 20 first released by latch 70, the pitman will let the fingers 62 drop to release the shock but as the shaft 26 continues to rotate at a more rapid rate to complete its revolution, the pitman 49 will draw the crank 50 down and, 25 through the pitman 52, effect a similar movement to the crank 53 to; through 59 and 61, swing the fingers 62 back to shock-receiving position.

From the foregoing description it will be 30 observed that when the clutch 17 is tripped the shock butts drop to the ground, the shock settler and compressor 37 revolves top forward one quarter turn at which position it is in a horizontal plane over the shock, 35 settling the shock solid on the ground; then fast clutch 33 comes into play, making full revolution of the shock settler and compressor 37 thereby compressing the shock and releasing it at substantially one operation 40 and automatically returning to its original position, ready for another shock.

When the clutch 17 is tripped, the shock formers, consisting of the rods 61 and fingers 62, rotate, thus forming the shock, closing 45 in the front and opening in the rear to let shock through when the fast clutch 33 is in operation, thereby compressing and releasing the shock and then rotate back to their original positions.

50 While I have shown only one form of my invention, it is obvious that it may partake of other forms while involving the same generic principle, the particular construction shown for the purpose of illustration being 55 capable of shocking nine to fifteen bundles with the shock untied although a tying attachment may be utilized, if desired.

In actual practice the shocks may be put in shock rows, convenient for a shock loader.

60 By practising my invention, the loose grain ordinarily lost along the bundle rows goes into the shocks and is thereby saved.

During the operation of the mechanism heretofore described, the leaves 38 and 39 65 will gather in the respective sides of the

head of the shock to protect the grain in an approved manner.

Having thus described my invention what I claim as new therein, and desire to secure by Letters-Patent is:

70

1. A shocker attachment for binders comprising a frame connected to the binder, shock holding means, shock compressing means, means for initially imparting a relatively slow movement to the compressing 75 means, and means for increasing the speed of the compressing means.

2. A shocker attachment for binders, comprising a frame, vertically and laterally swinging shock forming means carried by 80 said frame, shock compressing means, shock embracing means carried by the shock compressing means, and means for actuating all of the above mentioned means.

3. A shocker attachment for binders comprising a frame, longitudinally and laterally swinging shock forming members, a vertically swinging shock receiving end member, a shock compressor and shock up-ending means on the compressor, and means for 85 varying the speed of the shock compressor.

4. A shocker attachment for binders comprising grain receiving shock forming arms, and a compressor member having hinged 90 ends disposed in opposite directions.

5. A shocker attachment for binders, comprising grain receiving, shock forming members, a rotating compressor member, means for driving the compressor at a relatively slow speed for part of the rotation and at a 100 relatively fast speed to complete the rotation thereof.

6. A shocker attachment for binders, comprising grain receiving shock forming members, a shock butt support, a rotary compressor and settling member, means for releasing the formed shock, means carried by the compressor for up-ending the shock, means for partially rotating the compressor at a slow speed, and means for causing increased rotational speed of the compressor for the remainder of the rotation.

7. In a shocker attachment for binders, a frame, means on the frame for releasably receiving grain, and a shock compressor and 115 settling member, rotatably mounted on the frame.

8. A shocker attachment for binders comprising a frame, vertically and laterally swinging members carried by the frame for 120 receiving and forming the shock, means for imparting a movement to the members while they swing so that the forward parts of the members move together and the rear parts move away one from the other, and 125 a variable-speed, shock-settling means co-operating therewith.

9. A shocker attachment for binders comprising a frame to be connected to the binder, shock holding means, shock up-ending 130

- means, means for initially imparting a relatively slow movement to the shock up-ending means, and means for increasing the speed of the shock up-ending means.
- 5 10. A shocker attachment for binders comprising a frame to be connected to the binder, shock holding means, shock settling means, means for initially imparting a relatively slow movement to the shock settling means, 10 and means for increasing the speed of the shock settling means.
11. A shocker attachment for binders comprising a frame, shock up-ending means carried by the frame, a slow speed mechanism 15 and a fast speed mechanism for the shock up-ending means, means for initially rendering the slow speed mechanism effective for a portion of the movement of the shock up-ending means, and means for throwing 20 in the fast speed mechanism to complete the cycle of operation of the shock up-ending means.
12. A shocker attachment for binders comprising a frame, shock holding means, shock 25 settling and compressing means, and a variable speed mechanism for operating the shock settling and compressing means.
13. A shocker attachment for binders comprising a frame, a shock settling means at 30 one end of the frame, a butt support at the other end of the frame, and rounding, compressing and embracing members between the settling member and the butt support.
14. A shocker attachment for binders comprising a frame, shock forming members car- 35
- ried by the frame, and variable speed compressing, settling and shock up-ending members coöperative therewith.
15. A shocker attachment for binders comprising a frame, a shock holding means, a shock up-ending means controlling the shock holding means, means for initially rotating the shock up-ending means at slow speed, and means for completing the cycle of operation of the shock up-ending means at 40 relatively high speed.
16. A shocker attachment for binders comprising a frame, vertically and laterally swinging members carried by the frame for receiving and forming the shock, means for imparting a movement to the members while they swing so that the forward parts of the members move together and the rear parts move away one from the other, and variable speed shock-up-ending means coöperating 45 therewith.
17. In a shocker attachment for binders, a shock holder including connected cranks, a link normally holding the cranks in a determined position, a crank connected to the link, means for varying the speed of the crank connected to the link, means for releasing the crank to allow the connected cranks to move to releasing position, and means on the link operative during the rotation of the crank to which it is attached to restore the connected cranks to normal 50 position.
- In testimony whereof I affix my signature.
JAMES A. McELROY.
